UNITED STATES PATENT OFFICE

MARCEL MARIE EUGÈNE LANCRENON, OF PARIS, FRANCE

FERRO-CONCRETE FLOORING MEMBER

Application filed January 6, 1927, Serial No. 159,419, and in France January 20, 1926.

Due to the continual search for economy in the construction of flooring members in ferro-concrete, manufacturers have been led to adopt the method which consists in eliminating all stays and forms, and in utilizing pieces which are preliminarily moulded and which are placed in position after the setting of the concrete.

In certain of the devices employed, the beams alone are moulded in advance and the intermediate or flat parts are made up on the spot by the use of forms or hollow pieces disposed between the beams. In this method, the beam is provided with flat part which is subject to compression stress, only after it has been manufactured, and the connection between the two concrete parts which have been made at different periods may not always prove reliable. It should be further noted that in practice, even for ordinary spans, the beam is subject to sinking to such an extent that it may require a middle support between the end supports.

In other methods, on the contrary, the entire beam is prepared in advance together with the flat part which is subject to compression stress, thus affording various cross sections resembling those of structural steel beams. Such pieces are placed together so as to form the flooring. But in spite of all efforts to connect the pieces properly, they still remain distinct from one another. A beam which is loaded will thus bend slightly before it bears upon the adjacent beams, and so on throughout the series, and this defect is all the more serious from the fact that the moulded beams are made narrow to facilitate the handling, and each beam is designed to support only a small part of the load, so that the construction thus loses the principal advantage of concrete which is made up on the spot in a continuous manner and in which the stresses will be distributed to the outlying parts, even to quite a distance.

My invention relates to the construction of flooring which consists of juxtaposed elements or beams in which the aforesaid defects are eliminated by reason of a preliminary elastic deformation of the material and to their state of initial tension or com-

pression of the beam, the latter being further given a suitable shape for the obtainment of the qualities of lightness, strength and ready manufacture. The said beams, which are moulded in advance, have a general **C** shaped cross section, a ramp being formed at the end of each flange so that when the said beams are brought into contact they will be subjected to an elastic tension whereby they will be connected together before receiving any load. The top flange forms the floor surface for the upper story, whilst the bottom flange forms the ceiling of the lower story.

An embodiment of my said invention is shown by way of example in the appended drawings.

Fig. 1 is a perspective view of a portion of flooring which consists of beams according to the invention. Figs. 2, 3 and 4 show a mould for manufacturing the said beams; Figs. 2 and 3 show the said mould in cross section and elevation, in the respective positions for moulding and removal, and Fig 4 one of the plates limiting the length of the beam.

The beams 1 which form the flooring have in each case a **C**-shape, in which the two horizontal flanges 2 and 3 are terminated by the respective ramps 2' and 3', which are situated opposite one another. The vertical web is connected with the said flanges by the inclined planes or bevelled corners 4, 5 so that when the said beams are placed together, as shown in Fig. 1, the ramps 2', 3' of one beam will coincide exactly with the bevelled parts 4, 5 of the adjacent beam.

Suitable recesses 6 are formed in the said web at stated intervals, having an adequate shape, whereby the beam will be made lighter. In addition to the longitudinal reinforcing bars which are designed according to customary practice, the reinforcing elements comprise the **C**-shaped transverse elements which act chiefly against shearing stresses. These secondary members may be advantageously inclined at 45 degrees with reference to the axis of the beam.

Since the said beams are placed very close together, the ramps 2'-3' of each beam will bear against the bevelled parts 4-5 of the

adjacent beam, thus forcing the flanges apart in an elastic manner and producing a tension which is exercised before the structure receives any load, so that the several parts will be connected together in the most approved manner. By reason of the present form of construction, no part of the flooring will be overhung, since in each case the upper flange is caused to bear so to speak in the direction 10 of the axis of the adjacent beam. In this manner I am enabled to reduce the thickness to the minimum which is compatible with the proper manufacture.

The said beams can be moulded in a simple 15 and rapid manner by the use of a set of moulds whose essential features are shown in Figs. 2, 3 and 4. The moulding device consists of two parts comprising an inner and an outer part.

20 The outer part consists of two **U** iron members 8—8' with the webs placed in the vertical position and the flanges turned toward the exterior. Between the said members is disposed at the lower part a third 25 **U** iron member 9 with the web in the horizontal position and the flanges extending upwardly. The member 9 is held in contact with the members 8 and 8' by suitable clamping means, not shown.

30 The inner part of the mould consists of two angle pieces 10 and 10' in which the flanges are of unequal length and the angle is rounded; said pieces are pivoted together at 11, and each carries at the end of the long 35 flange an iron member 12—12' of triangular cross section. Upon this inner part are disposed the bosses 13 which are suitably spaced apart and are maintained by the pins 14 and serve to form the recesses 6 in the web 40 of the concrete beam, and they also serve to adjust the thickness of the web, as will be further specified.

The length of the concrete beam is limited by the members 15 having the form represented in Fig. 4 and comprising the apertures 16 through which may extend the steel 45 reinforcing bars for making connection with the other elements of the building.

The operation is as follows:

50 The internal core is put in place as shown in Fig. 2, with the triangular members 12—12' resting upon the flanges of the lower member 9. The concrete is placed between the members 8—8' and the internal core 55 10—10', and it is levelled off flush with the bosses 13 by means of a tool which forms at the same time the bevelled parts 4—5. When the concrete begins to set, the bosses 13 are removed through the apertures 6; 60 the clamps holding together the members 8—8' and the member 9 are removed, and the said core is lowered by bringing together its branches 10—10' (Fig. 3) and it is then drawn out in the lengthwise direction. The 65 setting of the beam can now be completed,

with its flanges resting upon the flanges of the member 9.

What I claim is:

1. A **C**-shaped building unit of reinforced concrete comprising a vertical portion the outer top and bottom corners of which are cut cantwise and two horizontal portions integral with the vertical portion and projecting from the top and bottom of the inner side of the vertical portion, the free ends of these horizontal portions being cut cantwise in a manner corresponding substantially to the cants on the vertical portion, and **C**-shaped reinforcing bars the end parts of which are disposed in the horizontal portions perpendicularly to the vertical portion and the middle part of which is disposed in the vertical portion at an angle of 45° with the horizontal.

2. A hollow concrete flooring including a plurality of parallel similarly disposed **C**-shaped beams each consisting of a vertical portion and two horizontal extensions, oppositely inclined slopes at the outer corners of the vertical portion of each beam, oppositely inclined slopes at the inner corners of the extensions and disposed substantially parallel to the corresponding slopes of the vertical portions of the adjacent beams and adapted to freely slide to allow the vertical portion of one beam to be wedged inside the channel of the adjacent beam and to open the extensions thereof, whereby the beams are mechanically connected more closely as the pressure between the beams is increased.

3. A hollow concrete flooring including a plurality of parallel beams disposed side by side, corners bevelled in opposed direction at the upper and lower ends of the sides of each beam adjacent another beam and facing a given direction, oppositely inclined slopes formed at the upper and facing the other direction, the cooperating bevelled corners and slopes having corresponding inclinations and being adapted to produce incident to their free sliding movement an elastic wedging of one of the beams whereby the latter are mechanically connected more closely as the beams are pressed together.

In testimony whereof I have affixed my signature.

MARCEL MARIE EUGÈNE LANCRENON.
